UNITED STATES PATENT OFFICE.

ARTHUR L. STAPLES, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

HANDLAMP SWITCH.

Application filed November 8, 1920. Serial No. 422,408.

To all whom it may concern:

Be it known that I, ARTHUR L. STAPLES, a citizen of the United States, residing at New Haven, in the county of New Haven, 5 State of Connecticut, have invented certain new and useful Improvements in Hand-lamp Switches; and I do hereby declare the following to be a full, clear, and exact description of the invention, such as will 10 enable others skilled in the art to which it appertains to make and use the same.

The present invention relates to portable electric lamps comprising a casing, a battery, and an incandescent lamp mounted 15 therein, and a contact device on the casing by which the flow of current from the battery to the lamp may be controlled at will.

In a portable lamp of this character, it is desirable that the user shall be able to 20 flash the lamp, that is, light it, for short periods of time, as in signaling, or for such a time as it is convenient for the operator to hold his thumb on the contact device. It is also desirable that means be provided for 25 closing the switch to light the lamp for a longer period of time and without the need for continuous thumb pressure on the contact mechanism, as explained at length in U. S. Letters Patent No. 1,349,860, issued to 30 me August 17, 1920.

It is an object of the present invention to provide a hand lamp with an improved contact mechanism so arranged that the lamp can be flashed and can be permanently lighted, as desired. The several parts are so designed as to permit efficient manufacture by 35 automatic metal working machines, and to permit of easy assembly into a reliable and effective contact mechanism. Inadvertent 40 closing of the circuit at the contact device is in large measure prevented, and any small irregularities either in form or in position of the several parts are adequately taken care of, so that reliable opening and closing 45 of the switch is at all times insured. The contact mechanism comprises a spring member manually operable for instantaneous contact with an opposed conductor, and locking means movable into engagement with the 50 spring member to hold it in closed circuit position when a continuous light is desired, this locking means in the preferred embodiment being itself locked against movement until 55 said spring member has been manually operated. This permits the hand lamp to be

carried about and roughly handled with reasonable assurance that the switch will not be closed accidentally and the battery thus exhausted to no useful purpose.

Other objects and advantages of the 60 present invention will become apparent from the following description, which is to be taken in conjunction with the accompanying drawings, wherein—

Fig. 1 is a sectional elevation of a hand 65 lamp constructed in accordance with the present invention;

Fig. 2 is an enlarged view of the contact device;

Fig. 3 is a section on the line 3—3 of Fig. 70 2 with the electrical circuit open;

Fig. 4 is a similar section with the circuit closed for continuous burning of the lamp;

Fig. 5 is a transverse section on the line 75 5—5 of Fig. 2;

Fig. 6 shows the contact mechanism as viewed from beneath;

Fig. 7 is an enlarged detail of a yielding contact element secured to the casing of the 80 lamp; and

Fig. 8 is a detail of the sliding thumb-actuated member by which continuous burning 85 of the light is effected.

Fig. 9 is a detail of the push button spring member.

In the embodiment illustrated, a casing 1 of fiber or other suitable material is provided at its bottom end with a threaded ring 2 on which is mounted a bottom cap 3 of metal carrying a coil spring 4 which engages 90 the naked bottom of the lowermost dry cell 5 and establishes electrical connection therewith. The uppermost dry cell 6 has its inner or carbon electrode 7 in contact with the inner terminal of the lamp 8, and the outer or threaded terminal of the lamp is connected, as through a reflector 9, with the front curved and yielding end of a conductor 10, which may be in the form of a flat strip, and leads to a contact device conveniently 95 positioned near the middle of the casing. The lamp is provided with a lens 11 held in position by a flanged threaded collar 12 having engagement with a threaded ring 13 mounted at the front end of tube 1. Preferably 100 the periphery of reflector 9 is insulated from collar 12 and ring 13 to prevent inadvertent lighting of the lamp when the lamp is laid down on a metal surface.

The contact device comprises an escutche- 110

2

eon 14 connected to the bottom of the lowermost dry cell 5, as through a flat strip 15, the upper end of which is riveted to the escutcheon, and the lower end of which is tucked under and makes connection with the inwardly extending flange of ring 2, and so is in electrical connection with the battery through cap 3 and spring 4. Mounted on this escutcheon plate and preferably integral therewith is a housing 16. Within this housing is a contact member 17, preferably in the form of a spring fastened to the housing at its lower end, as by means of a rivet 18, and movable at its upper end 15 into and out of contact with a yielding contact element 19, which preferably is a flat spring strip secured under the lowermost of the two rivets 10' by which strip 10 is securely anchored to the casing. Element 20 19 may advantageously extend beyond rivet 10' and have this extension bent down at 19' to seat in a hole in the fiber of the casing. This prevents the element 19 from swinging on rivet 10' as a pivot.

25 Spring member 17 has a relatively large push button or thumb-piece 20 which is exposed at an opening in housing 16, but does not project appreciably above the outer face or edge of the housing.

30 The structure above described can be manipulated by pressure on the push button or thumb-piece 20 of the flexible spring member 17 to flash the lamp. The structure can be laid down on a flat surface without 35 out danger of closing the switch, for the thumb-piece 20 is protected by the encircling edge of the housing.

To permit the lamp to remain lighted without the need for continuous pressure 40 on the thumb-piece 20, there is provided a locking means comprising an auxiliary thumb-actuated member 22, preferably in the form of a flat plate, stamped from sheet metal to the shape shown in dotted lines 45 in Fig. 8, with projecting knurled lugs 23 which, during the operations of assembly, can be bent down to the positions shown in full lines (Fig. 8), to leave longitudinal recesses 24 which permit sliding movement 50 of the thumb-piece with respect to the housing as illustrated in Figs. 3 and 4.

55 Spring member 17 and its integral push button 20 are slotted to receive the sliding thumb-piece 22, the inner straight edge of which has a square corner 25 which initially strikes against the end of the slot in spring member 17 (Fig. 3) to lock the sliding thumb-piece against movement. But after inward pressure on push button 20 60 and the resultant swinging of spring member 17, this corner 25 will clear member 17 (Fig. 4) and can then be pushed forward to lock that spring member in its depressed or circuit-closing position. When the parts 65 are in the position shown in Fig. 4, the out-

ward pressure of spring 17 frictionally engages the inner edge of the sliding thumb-piece 22 and so lessens the danger of accidental movement of that thumb-piece backward to the position shown in Fig. 3. 70

Spring contact member 17 yieldingly holds the parts in the position shown in Fig. 4, while the lamp is being used, but does not prevent return of the auxiliary thumb-piece 22 to the retracted position 75 shown in Fig. 3. It will therefore be understood that with the parts positioned as shown in Fig. 3, the push button or thumb-piece 20 can be freely manipulated to flash the lamp and that when a permanent light 80 is desired, the thumb of the operator can be wiped upward across the thumb-piece 20 to unlock shoulder 25 and thereafter can slide auxiliary thumb-piece 22 into the position shown in Fig. 4 and the lamp will 85 burn continuously. It is in these manipulations that the yielding character of contact element 19 becomes particularly important, for any slight inaccuracy of adjustment in the relation of spring member 90 17 and sliding member 22 at the engaging shoulder 25, is compensated for by the yielding character of element 19. The push button can be depressed far enough to easily clear shoulder 25 from the slot in spring 95 element 17, and yet when the thumb pressure on the button is removed, and the spring element comes back into engagement with the straight face of member 22, as shown in Fig. 4, there will still be electrical 100 connection between the two opposed contact elements of the switch. The bent end 19' of element 19 being embedded in the fiber, prevents that element from swinging on its rivet, and, likewise, the two rivets 10' hold strip 10 against displacement when end-cap 12 is unscrewed and the reflector and lens are taken out for adjustment or renewal of the lamp bulb.

I am aware that various changes may be 110 made in the details of the present invention without departing from the spirit thereof as defined by the appended claims.

I claim:

1. A contact device for battery hand lamps 115 comprising a spring member having a thumb piece manually operable to flex the spring member into circuit-closing position, the exposed part of said thumb piece being slotted, and means manually movable in the slot of 120 said thumb piece and into engagement with said spring member to lock said member in closed position.

2. A contact device for battery hand lamps comprising a yielding contact element extending longitudinally of the hand lamp casing and secured to the outside thereof, a 125 spring member manually operable for instantaneous contact with the yielding contact, locking means movable into engage- 130

ment with said spring member to hold said member in closed position when a continuous light is desired, said locking means being itself locked against movement until said

5 spring member has been manually operated.

3. A contact device for battery hand lamps comprising a yielding contact element, a spring member manually operable for instantaneous contact therewith, said spring member having an exposed longitudinal slot, locking means movable along said slot into engagement with said spring member to hold said member in closed position when a continuous light is desired, said locking means

15 being itself locked against movement until said spring member has been manually operated.

4. A contact device for battery hand lamps comprising a yielding contact element, an opposed leaf-spring having a push button by which it may be manually operated to flash the lamp, said push button having a slot, a sliding thumb-actuated member positioned in said slot and engageable with said spring

25 to hold it in circuit-closing position, said sliding member being locked against said sliding movement until after said spring member has been manually depressed.

5. A contact device for battery hand lamps comprising a housing, a yielding contact element within said housing and secured to the outside of the hand lamp casing, an opposed leaf-spring having a push button by which it may be manually operated to flash the

35 lamp, a sliding thumb-actuated member engageable with said spring to hold it in circuit-closing position, said sliding member being locked against said sliding movement until after said spring member has been

40 manually depressed.

6. A contact device for battery hand lamps comprising a housing, a yielding contact element enclosed in said housing and extending longitudinally thereof, an opposed

45 spring member fastened at one end to said housing and movable at its other end to close the circuit, said spring member having an exposed longitudinal slot, and means positioned in said slot and movable along said

50 housing into locking engagement with the free end of said spring member when the circuit is to remain closed.

7. A contact device for battery hand lamps comprising a housing, a yielding contact element enclosed in said housing and fixed to the outside of the hand lamp casing, an opposed spring member fastened at one end to said housing and movable at its other end to close the circuit, and means movable along

60 said housing into engagement with the outer face of the free end of said spring member to lock said member in closed circuit position.

8. A contact device for battery hand lamps

65 comprising a housing, a spring member se-

cured at one end to said housing and having a thumb piece at its other end manually operable to flex the spring member and thereby close the circuit through the lamp, said thumb piece having a slot extending across its exposed face, and an auxiliary thumb-piece positioned in said slot and mounted to slide along said housing and carrying means engageable with said spring member to lock it in closed position when continuous lighting of the lamp is desired.

9. A contact device for battery hand lamps comprising a housing, a spring member mounted therein and movable to close the circuit, a push button for actuating said spring member, said push button having a slot, and a thumb-piece positioned in said slot and mounted to slide in one direction along said housing, and having means to hold the spring member in closed-circuit position, said thumb-piece being itself so shaped as to be locked by the spring member until after the spring member has been depressed.

10. A contact device for battery hand lamps comprising a fiber casing, a conductor on the inside of said casing and secured thereto by a pair of rivets, a yielding contact element secured to the outside of said casing and secured by one of said rivets, a housing enclosing said rivets and said yielding element, and a swinging spring member in said housing manually movable into engagement with said yielding element when the lamp is to be lighted.

11. A contact device for battery hand lamps comprising a fiber casing, a yielding contact element secured to the outside of said casing, a housing enclosing said yielding element, a spring member positioned in said housing and manually operable for instantaneous contact with said yielding element, locking means movable into engagement with said spring member to hold said member in closed position when a continuous light is desired, said locking means being itself locked against movement until said member has been manually operated.

12. A contact device for battery hand lamps comprising a fiber casing having a conductor on the inside thereof and riveted thereto, a yielding contact element on the outside of said casing and secured by one of said rivets, a housing enclosing said yielding contact element, a spring member mounted in said housing and movable into contact with said yielding element to close the circuit, a push button for actuating said spring member, said push button having a slot, and a thumb-piece positioned in said slot and mounted to slide in one direction along said housing and having means to hold the spring member in closed-circuit position, said thumb-piece being itself so shaped as to be locked by the spring mem-

ber until after the spring member has been depressed.

13. A contact device for battery hand lamps comprising a housing, a spring member secured at one end to said housing and having a push button at its other end manually operable to flex the spring member and thereby close the circuit through the lamp, said push button having a slot, and a thumb-piece positioned in said slot and mounted to slide along said housing, said thumb-piece consisting of a flat plate notched to simultaneously engage the housing on both sides of the push button and shaped to engage with said spring member to lock it in closed position when continuous lighting of the lamp is desired.

14. A contact device for battery hand

lamps comprising a housing, a spring member secured at one end to said housing and 20 having a push button at its other end manually operable to flex the spring member and thereby close the circuit through the lamp, said push button having a slot, and a thumb-piece positioned in said slot and mounted to 25 slide along said housing, said thumb-piece consisting of a flat plate notched to slidingly engage the housing on both sides of said push button, and having means to hold the spring member in closed-circuit position 30 when desired, said thumb-piece being itself so shaped as to be locked by the spring member until after the spring member has been depressed.

In testimony whereof I affix my signature.

ARTHUR L. STAPLES.
